UNITED STATES PATENT OFFICE.

JOHN TAMBERLIN, OF PHILADELPHIA, PENNSYLVANIA, ASSIGNOR TO THE GEORGE W. BLABON COMPANY, OF PHILADELPHIA, PENNSYLVANIA, A CORPORATION OF PENNSYLVANIA.

RUG-PRINTING MACHINE.

Application filed November 16, 1921. Serial No. 515,485.

To all whom it may concern:

Be it known that I, JOHN TAMBERLIN, a citizen of the United States, residing at Philadelphia, in the county of Philadelphia and State of Pennsylvania, have invented 5 certain Improvements in Rug-Printing Machines, of which the following is a specification.

The improvements of this invention are 10 designed more particularly for printing rugs such as predetermined lengths of linoleum or other floor coverings having designs provided with rectangular borders.

The improvements are adapted to be applied 15 to usual types of block printing machines in which an intermittently movable carrier mechanism translates a fabric step by step over a bed and under printing blocks or heads that are reciprocated in predetermined 20 relation, to impress their particular configurations upon the fabric during the intervals between its movements and thus produce the desired pattern or design thereon.

25 The invention is characterized by its improved means for regulating the operations of the printing heads by a master controller, thereby timing the movements of the heads in predetermined relation and regulating 30 the lengths of the design or pattern of the respective rugs.

In the accompanying drawings, Fig. 1 is a broken side elevation of the forward end of a printing machine provided with my 35 improvements; Fig. 2 is a broken side elevation of the rear end of the same machine; Fig. 3 is a side elevation of a detail for stopping the operation of the heads; Fig. 4 is a broken side view and Fig. 5 is a transverse 40 sectional view of means for controlling the operations of the blocks for printing intermediate sections of the design or pattern; Fig. 6 is a broken side view and Fig. 7 is a transverse sectional view of means for 45 controlling the operations of the blocks for printing the end sections of the design or pattern; Fig. 8 is a broken side view and Fig. 9 is a transverse sectional view of the master block controlling mechanism, and 50 Fig. 10 is a diagrammatic view of a section

of fabric adapted to be printed by the mechanism.

The machine shown in the drawings, by way of illustrating an application of my improvements, comprises the frame 1 having 55 journalled therein the shafts 2 and 3 on which are fixed the respective wheels 4 and 5 for carrying the pin belts 6, the latter engaging and carrying the fabric 7 over the bed 8. Cam bars 9, provided with the 60 notches 10, are reciprocated on the supporting rollers 11 and beneath the guide rollers 12 journalled in the frame; the movement being effected by the rod 13 which is connected with the bars and actuated by the 65 eccentric 14 on the wheel 15 journalled in the frame and driven in any suitable manner. Racks 16, fixed to the bars 9, rock the gears 17 on the shaft 3 and oscillate the pawls 18 fixed to the gears, the pawls acting 70 upon the ratchet wheels 19 fixed on the shaft. One of the racks reciprocates below the axis of the shaft 3, and the other rack (not shown) reciprocates above the axis of the shaft 3; the teeth of the respective 75 ratchet wheels 19 being so arranged relatively to one another that one rack, through its pawl and ratchet wheel, rotates the shaft one step upon the movement of the bars 9 in one direction and the other rack, 80 through its pawl and ratchet wheel, rotates the shaft another step upon the movement of the bars 9 in the reverse direction, so as to operate the carrier mechanism intermittently and advance the 85 fabric step by step. Slide bars or struts 20, 20' and 20'', movable vertically in the guides 21, 21' and 21'' carried by the frame, are provided at their lower ends with the rollers 22, 22' and 22'', adapted to ride on 90 the cam bars 9, and carry at their upper ends the printing heads or blocks 23, 23' and 23'' which are adapted to fall into contact with the fabric on the bed 8 as the notches 10 reach their central position with relation to 95 the rollers, the heads being elevated by the movement of the bars from such position. Dogs 24, 24' and 24'', fulcrumed on the frame, are adapted for engaging the respective bars 20, 20' and 20'', to hold them in 100

their elevated positions, and connected inking mechanisms 25, 25' and 25'' movable on tracks 26 apply the desired colors to the respective heads when elevated.

5 The foregoing construction, of known character, is provided, according to my invention, with the pins or spindles 27, 27' and 27'' which are carried by the frame 1 and carry the respective flanged discs 28, 10 28' and 28'' provided with the respective depending arms 29, 29' and 29'' for rocking them. A bar 30 has pivotally connected thereto the respective arms 29, 29' and 29'', and also the oscillatory lever 31 carried by the 15 pin 32, a cord or chain 33 passing from the rear end of the bar over the roller 34 to a weight 35 for drawing the bar back to a limited position. A pin 36 on the cam bar 9, in the movement of the latter in the 20 direction of the arrow, strikes the arm 31 to move the bar 30 against the action of the weight 35; and a pin 37 on the bar 9, in the movement of the latter in the opposite direction, acts through a lever 38 on a stud 39 25 to move the bar 30 against the action of the weight. Thereby each movement of the bar 9 is accompanied by a reciprocation of the bar 30 to advance and retract or oscillate the corresponding arms 29, 29' and 29'' together with the respective discs 28, 28' and 28'' through their complete arcs of movement.

The discs 28, 28' and 28'' carry the respective actuating pawls 40, 40' and 40'' (provided with disengaging fingers 41, 41' and 41'' projecting through the respective peripheries of the discs) which engage the respective ratchets 42, 42' and 42'' journaled on the respective spindles 27, 27' and 27'', between the respective flanged discs 28 and 43, 28' and 43', 28'' and 43'', the discs being journaled on hubs of the respective ratchets. The discs 28' and 43'' carry the respective dogs 44' and 44'' for engaging the respective ratchets 42' and 42'', the dog 44' having a tail piece 44^a for engaging a stud 43^a on the disc 43'. The teeth upon the respective ratchets 42' and 42'' are arranged in three pairs, each pair being spaced from the adjacent pairs by a peripheral section of greater length than the effective "throw" of the respective dogs 40' and 40'', which dogs oscillate idly over these peripheral sections during the printing of the body portions of the rug and until teeth of the respective ratchet wheels are brought into the respective paths of the dogs 40' and 40'' by the actions of the respective dogs 44' and 44''. The dog 44' is normally held out of engagement with the teeth of the ratchet 42' by the engagement with its tail 44^a of the stud 43^a, the stud and tail being oscillated together by the respective discs 28' and 43' connected respectively with the rod 30 and

link 52. When, however, the head 23 is held 65 in the elevated position the link does not oscillate the disc 43' and consequently the movement of the rod 30 will move the tail of the dog 44' out from under the stud 43^a when the head 23 is in the elevated position. 70

Cams 45, 45' and 45'', fixed to the respective ratchets 42, 42' and 42'' are engaged by the respective bearing devices 46, 46' and 46'' on the longer and laterally extending arms of crank levers 47, 47' and 47'' which 75 are fulcrumed on the frame, the shorter arms of these levers being connected by the respective links 48, 48' and 48'' with the respective dogs 24, 24' and 24''. Hence when the high points of the cams 45, 45' and 80 45'' engage the respective bearings 46, 46' and 46'', the respective dogs 24, 24' and 24'' will be drawn by the intermediate devices into positions for engaging the respective studs 20, 20' and 20'' to hold the corresponding heads 23, 23' and 23'' in their elevated positions, and when the bearings of the crank levers engage the low points of the corresponding cams, the dogs will be retracted to permit the corresponding heads 90 to fall.

The cam 45 is provided with the consecutively numbered studs 49 corresponding to the equally spaced teeth of the ratchet 42, this cam being turned in accordance with this gauge to any desired position with relation to the cams 45' and 45'' and the relative operations of the dogs 24, 24' and 24'' together with the heads 23, 23' and 23'' being regulated thereby. 95

The bars 20, 20' and 20'' are connected by the respective links 50, 50' and 50'' pivoted thereto with the longer arms of crank levers 51, 51' and 51'' which are fulcrumed on the frame, the shorter arms of these 105 levers being connected by links or rods 52, 52' and 52'' with the respective arms 53, 53' and 53'' on respective discs 43', 43'', which are thereby rocked by the movements of the corresponding heads connected therewith. 110

A dog 54, pivoted to the frame, is adapted for engaging a device 55 on the bar 30 for holding the latter stationary in the position to which it is moved by the action of the stud 36 on the lever 31 or the action of the 115 stud 37 on the lever 38, the parts actuated by the bar 30 being thus rendered inactive. An oscillatory arm 56, provided with the stud 57 adapted for engaging the top of the dog 54 on either side of its fulcrum, can be 120 thrown so as to depress the dog to position for engaging the device 55 when carried thereunder by the rod 30, whereby the latter is held stationary, the position of the arm being reversed to elevate the dog so that it 125 is removed from the path of the device 55.

In the operation of the machine, the intermittent movements of the web or fab-

ric 7 alternate with oscillations of the rods 30, and the printing heads are reciprocated by the cams 9 so as to engage the web 7 while it is at rest. The descent of the printing heads is substantially concurrent with the movement of the rods 30 toward the front (right) of the machine to move the control pawls 40, 40', 44' and 40'' anticlockwise, and the elevation of the printing heads by the cams 9 is substantially concurrent with the movement of the rods 30 toward the rear (left) of the machine to move the pawls clockwise.

If the ratchet wheel 42 of the master cam 45 is provided with seven teeth, as shown, the body-printing heads 23, 23'' will normally reciprocate six times to each reciprocation of the border-printing heads 23'; while if the ratchet wheel 42 of the master cam 45 is provided with some other number of teeth, the body-printing heads will reciprocate as many more times than the border-printing heads as there are teeth on the ratchet wheel of the master cam less one.

The cycle of operations of the machine may be conveniently considered as starting with the ratchet wheel 42 so positioned that the part 46 lies at the foot of the protuberance on the cam 45, the printing heads all elevated and the rod 30 moved all the way toward the rear (left) of the machine. In this position of the mechanism, the border-printing head 23' will be latched up, the part 46' of the lever 47' being engaged by one of the protuberances of the cam 45. The ratchet wheel 42' is so disposed that the pawl 40' lies about midway between two pairs of teeth, and the pawl 44' has its tail 44^a engaged by the stud 43^a on the disk 43'. The head 23'' will be unlatched, the part 46'' lying in a depression between two protuberances of the cam 45''. The ratchet wheel 42'' is so disposed that the pawl 40'' lies about midway between two pairs of teeth on the ratchet wheel, and the pawl 44'' is held against movement by its connection with the latched head 23'.

The descent of the body printing heads 23, 23'', due to the movement of the cams 9, is accompanied by the movement of the rod 30 toward the right, resulting in the anti-clockwise movement of the pawls 40, 40', 44' and 40''. The descent of the head 23 also acts, through the parts 50, 51, 52, 53, and 43', to move the stud 43^a anti-clockwise in synchronism with the movement of the tail 44^a of the pawl 44', thereby preventing engagement thereof with a tooth of the ratchet wheel 42' over which it is suspended. The pawl 40 is thus placed in position to engage a tooth of the ratchet wheel 42, but the pawls 40' and 40'' slide idly on the peripheral sections of the ratchet wheels 42' and 42'' between two of

the pairs of teeth thereof. The border-printing head and pawl 44'' remain stationary.

Upon the upward movement of the body-printing heads, the rod 30 is shifted to the left, resulting in the advancement of the ratchet wheel 42 by the pawl 40 so that the protuberance of the cam 45 engages and elevates the part 46 on the lever 47, thereby locking the head 23 in the elevated position. This movement of the rod 30 has no effect upon the ratchet wheels 42' and 42'', since the pawls 40' and 40'' slide idly between the respective pairs of teeth thereof, the pawl 44' is held out of action by the synchronous movement therewith of the stud 43^a, and the pawl 44'' is held stationary by the latched head 23'.

During the next movement of the rod 30 to the right, the head 23 is latched in the elevated position, to permit a border section 85 to pass unprinted beneath it; the disk 43' and stud 43^a being thereby held against movement. The movement of the rod 30 moves the pawl 40 anti-clockwise into position for engaging the next tooth of the ratchet 42; moves the pawl 44' anti-clockwise so that its tail 44^a is drawn out from under the now stationary stud 43^a and its head drops down into engagement with the first tooth of a pair on the ratchet wheel 95 42'. The pawls 40' and 40'' still move idly between pairs of teeth on the respective ratchet wheels 42' and 42'' and the pawl 44'' still remains stationary.

As the rod 30 again moves to the left, it advances the pawl 40 clockwise to move the protuberance of the cam 45 from under the device 46 of the lever 47, thereby unlatching the head 23; it advances the pawl 44' clockwise so as to rotate the ratchet 42' and bring the first tooth of a succeeding pair of teeth into the path of movement of the pawl 40'; the cam 45' being thereby turned so that the device 46' lies near the end of its supporting protuberance. The pawls 40' and 40'' still ride idly and the head 23' and pawl 44'' remain stationary.

The next movement of the bar 30 to the right moves the pawl 40 anti-clockwise into position for engaging a tooth of the ratchet 115 42; moves the pawl 40' anti-clockwise into position for engaging the tooth of the ratchet 42' brought into its path by the previous action of the pawl 44'; and moves the pawl 44' anti-clockwise, but since the unlatched head 23 simultaneously descends and moves the stud 43^a engaging the tail 44^a in synchronism therewith, the pawl 44' is prevented from engaging the ratchet 42'. The pawl 40'' rides idly and the head 23' and pawl 44'' remain stationary.

The next movement of the rod 30 to the left moves the pawl 40 clockwise to advance

the ratchet wheel 42 one step; moves the pawl 40' to advance the ratchet wheel 42' one step and move the protuberance of the cam 45' from under the part 46', thereby permitting the lever 47' to rock and unlatch the border-printing head 23'. The ascent of the head 23 moves the stud 43^a in synchronism with the clockwise movement of the pawl 44' and by its engagement with the tail 44^a keeps such pawl 44' out of action. The pawl 40' moves idly and the pawl 44'' remains stationary.

10 The next movement of the rod 30 to the right is accompanied by the descent of the body-printing heads 23, 23'' and the border-printing head 23' and effects the movement of the pawl 40 into position for engaging a tooth of the ratchet 42; and the movement of the pawl 40' into position for engaging the second tooth of a pair of the ratchet wheels 42'. The pawl 44' is held out of engagement by the synchronous movement therewith of the stud 43^a, and the pawl 40' moves idly. The descent of the head 23', however, moves the pawl 44'' into position for engaging the first tooth of a pair on the ratchet wheel 42''.

15 The movement of the rod 30 to the left, accompanied by the upward movement of all the heads, moves the pawl 40 to advance the ratchet wheel 42 one step; and moves the pawl 40' in engagement with the second tooth of a pair on the ratchet wheel 42' to move the latter one step, and force a succeeding protuberance of the cam 45' under the device 46' to rock the lever 47' and latch the head 23' in the elevated position. The pawl 44' is held out of engagement by the synchronous movement therewith of the stud 43^a and the pawl 40'' moves idly. The upward movement of the head 23', however, moves the pawl 44'' clockwise to rotate the ratchet wheel 42'' so as to bring the first of a succeeding pair of teeth into the path of the pawl 40'' and move the cam 45'' so that the device 46'' is adjacent to the base of an elevating protuberance on the cam.

20 On the next movement of the rod 30 to the right, the pawl 40 is positioned to engage a tooth of the ratchet wheel 42; the pawl 40' is moved idly between two pairs of teeth on the ratchet wheel 42'; the pawl 44' is held out of action by the synchronous movement of the stud 43^a by the head 23; and the pawl 40'' is moved into position for engaging the tooth moved into its path by the previous action of the pawl 44'', which is now held stationary by its connection with the patched head 23'.

25 The movement of the rod 30 to the left, moves clockwise the pawl 40 to advance the ratchet wheel 42 one step; moves clockwise the pawl 40' which slides idly between two pairs of teeth of the ratchet wheel 40';

30 moves clockwise the pawl 44' which is held out of action by the synchronous movement of the stud 43^a due to the rise of the head 23; and moves the pawl 40'' clockwise in engagement with the first of a pair of teeth on the ratchet wheel 42'' to move a protuberance of the cam 45'' under the part 46'' of the lever 47'', which is thereby rocked to latch the head 23'' in the upper position.

35 The next movement of the rod 30 to the right, positions the pawl 40 to engage a tooth of the ratchet wheel 42; moves the pawl 40' idly as before; moves the pawl 44' idly because of the engagement therewith of the stud 43^a actuated by the head 23; and positions the pawl 40'' to engage the second tooth of a pair of teeth thereon. The movement of the rod 30 to the left moves the pawl 40 clockwise to advance the ratchet wheel 42 one step; moves the pawls 40' and 44' idly as before; and moves the pawl 40'' clockwise to advance the ratchet wheel 42'' one step and move the elevating protuberance from under the part 46'' of the lever 47'', thereby permitting the latter to rock and unlatch the head 23''. During these movements of the rod 30, the pawl 44'' is held stationary by its connection with the latched head 23'.

40 The reciprocations of the body-printing heads and the oscillations of the rod 30 is continued until the protuberance of the cam 45 again elevates the part 46 of the lever 47, when the operations described are repeated.

45 The operation of additional printing heads may be controlled in the same manner as control is effected of the heads in the operation described, whereby any desired number of colors may be impressed upon the body and borders of a rug.

50 From the foregoing, it will be understood that the reciprocation or latching of the first printing head is positively controlled by the master cam 45; the reciprocation or latching of the second printing head is controlled through the action of the first printing head; the reciprocation or latching of the third printing head is controlled through the action of the second printing head, and so on, so that an adjustment of the master cam alone will regulate the actions of all the printing heads in sequence. Hence if it is desired to make a longer rug than would be normally made with the use of the ratchet wheel 42, the pawl 40 may be disengaged from the ratchet wheel 42 (by operating the finger 41) to defer to any desired extent the elevation of the lever 47 by the cam 45, thereby permitting the head 23 to make any desired number of impressions. Since the actions of the remaining printing heads are controlled by the action of the head 23, the impressions of the additional heads will follow in proper sequence. Conversely, if it is

- desired to shorten a particular rug, the cam 45 may be manually advanced to cause the protuberance thereon to elevate the part 46 and rock the lever 47, thereby latching the 5 head 23 before the normal number of impressions have been made thereby; but the remaining heads, being regulated by the first head, will act at the proper time to complete the smaller rug.
- 10 Having described my invention, I claim:—
1. In a printing machine, the combination with a plurality of reciprocatory heads and means for locking them out of action, of means, comprising an adjustable master controller and mechanism controlled by a head or heads aforesaid, for releasing said heads in predetermined relation.
  2. In a printing machine, the combination of a plurality of reciprocatory heads, and 20 means for regulating the relative movements of said heads in sequence and comprising cams and mechanisms whereby the reciprocations of said heads regulate the relative movements of said cams.
  3. In a printing machine, the combination with a plurality of vertically reciprocatory heads, means for elevating said heads, and means for locking said heads in their elevated positions, of means comprising a plurality of revolute cams for operating the locking means, and means for revolving said cams in predetermined relation, said means last named comprising mechanisms whereby the reciprocations of said heads regulate the 35 relative movements of said cams.
  4. In a printing machine, the combination with a plurality of vertically reciprocatory heads, means for elevating said heads, and devices for locking said heads in their elevated positions, of means comprising a plurality of revolute cams for operating the locking devices, ratchets for operating said cams, and mechanisms operated by the means for elevating said heads and by the reciprocations of said heads for operating said ratchets in predetermined relation.
  5. In a printing machine, the combination with a plurality of reciprocatory heads, cam mechanism for elevating said heads, 50 and dogs for locking said heads in their elevated positions, of means comprising a plurality of revolute cams for operating said dogs, devices fixed to said cams for turning them, mechanisms operated by said cam mechanism for turning said cams, and means whereby the reciprocations of said heads regulate the operations of said cams.
  6. In a printing machine, the combination with a vertically reciprocatory head, elevating means for said head and locking means for holding said head in its elevated position, of a revolute cam and a device for operating it whereby the locking means are operated, and means operating under con-
- trol of said elevating means whereby said device is operated, said cam and device being adjustable relatively to said means for operating the same whereby the actions of said locking device and head can be varied.
7. In a printing machine, the combination 70 with a vertically reciprocatory head and a device for locking said head in its elevated position, of means comprising a revolute cam for operating said locking device, ratchet mechanism for turning said cam intermittently and means for elevating said head and operating said ratchet mechanism in predetermined relation.
8. In a printing machine, the combination 75 with a pair of vertically reciprocatory heads and devices for locking said heads in their elevated positions, of mechanisms comprising revolute cams for operating said devices, mechanisms for turning said cams intermittently, means comprising cams for elevating said heads, means operated by said means last named for operating said mechanisms last named, and means whereby the movements of one of said heads regulates the operations of the other of said heads.
9. In a printing machine, the combination 80 with a pair of vertically reciprocatory heads and devices for locking the respective heads out of action, of a revolute cam and means whereby it operates one of said devices, means for revolving said cam intermittently, a second revolute cam and means whereby it operates the other of said devices, and mechanisms for operating said cams in predetermined relation, said mechanisms comprising means whereby the movements of said head first named regulates the movements of said cam second named.
10. In a printing machine, the combination 85 with a pair of vertically reciprocatory heads and devices for locking said heads in their elevated positions, of a manually revolute cam, mechanism whereby said cam operates one of said devices to disengage the head locked thereby, ratchet mechanism for revolving said cam, a second revolute cam, mechanism whereby said cam second named operates the other of said devices to disengage the head locked thereby, ratchet mechanism for operating said cam second named, means for connecting said ratchet mechanisms in cooperative relation, and means whereby said head first named is connected with and controls the action of said ratchet mechanism second named.
11. In a printing machine, the combination 95 with a plurality of vertically reciprocatory heads and devices for locking said heads in their elevated positions, of mechanisms comprising revolute ratchets and cams fixed thereto for operating the respective devices to disengage said heads, mechanisms for connecting said ratchet mecha-

nisms and operating them in synchronous relation, and mechanism whereby the reciprocations of heads aforesaid regulates the actions of ratchet mechanisms aforesaid to regulate the relative actions of said devices and heads.

12. In a printing machine, the combination with a plurality of vertically reciprocatory heads and devices for locking said heads in their elevated positions, of a plurality of dissimilar revoluble cams, means comprising levers adapted to be rocked by said cams whereby said devices are operated, ratchets fixed to the respective cams, oscillatory pawls for operating said ratchets, means connecting said pawls whereby they are operated in synchronous relation, and mechanisms operated by the movements of said heads for controlling the operations of the pawl and ratchet mechanism for respective adjacent heads, whereby said heads are engaged and disengaged by said devices in predetermined relation.

13. In a printing machine, the combination with a plurality of vertically reciprocatory heads and devices for locking said heads in their elevated positions, of a plurality of revoluble cams, mechanism whereby said cams operate said devices, ratchet mechanisms for operating said cams, a bar connecting said ratchet mechanisms for operating their actuating elements together, oscillatory devices for controlling the operations of ratchet mechanisms aforesaid, means whereby the movements of said heads operate said oscillatory devices, means for elevating said heads, and means for moving a fabric intermittently under said heads when elevated.

14. In a printing machine, the combination with a series of vertically reciprocatory printing heads, means for elevating said heads and devices for locking them in elevated position, of means comprising a revoluble cam and a ratchet fixed thereto for operating the device which locks the first of said heads, an oscillatory pawl for operating said ratchet, means comprising a revoluble cam and a ratchet fixed thereto for operating the device which locks the second of said heads, a pair of oscillatory pawls for operating said ratchet second named, means for oscillating said pawls first named and said pair of pawls together, means comprising an oscillatory device connected with the first head whereby the movement of the latter disengages one of said pair of pawls to delay the operation of the corresponding ratchet, means comprising a revoluble cam connected with the second head whereby the device which locks the third of said heads, independently oscillatory pawls for operating said ratchet third named, means and a ratchet fixed thereto for operating the

movements of the latter operates one of said independently oscillatory pawls, and means whereby the other of said independently oscillatory pawls is connected with and operated by said pawl first named.

15. In a rug printing machine, the combination with means for moving a fabric intermittently, a plurality of vertically movable heads for printing said fabric and means for elevating said heads and moving said fabric in synchronous relation, of means for holding said heads out of action and operating them in predetermined relation to print a rug of predetermined length and means comprising mechanisms controlled by the reciprocations of said heads for regulating the reciprocations of said heads and the length of the rug printed thereby.

16. In a rug printing machine, the combination with means for moving a fabric intermittently, a plurality of vertically movable heads for printing said fabric and means for elevating said heads and moving said fabric in synchronous relation, of means for holding said heads out of action and releasing them in predetermined relation to print a rug of predetermined length, means comprising a manually adjustable master cam for regulating the reciprocations of a head for making the intermediate sections of the rug pattern and means controlled by said head last named for regulating the movement of a head for making border sections of the rug pattern and thereby regulating the length of such pattern.

17. In a printing machine, the combination with means for moving a fabric intermittently, a plurality of vertically movable heads for printing said fabric, and means comprising a reciprocatory cam bar for elevating said heads and moving said fabric in synchronous relation, of locking mechanism for holding said heads out of action and releasing them in predetermined relation to print a rug of predetermined length, said mechanism comprising a plurality of revoluble cams, means whereby said cams operate said locking mechanisms, means comprising a reciprocatory bar whereby said cams are revolved in synchronous relation, and means whereby said cam bar operates said reciprocatory bar.

18. In a rug printing machine, the combination with means for moving a fabric intermittently, a plurality of vertically movable heads for printing said fabric and means comprising a reciprocatory cam bar for elevating said heads and moving said fabric in synchronous relation, of locking mechanisms for holding said heads out of action and releasing them in predetermined relation to print a pattern of predetermined length, said mechanisms comprising a plurality of revoluble cams, means whereby cams aforesaid

operate locking mechanisms aforesaid, means connected with said heads whereby the movements thereof regulate the movements of cams aforesaid, a master cam for 5 operating the locking mechanism of one of said heads, means comprising a reciprocatory bar for operating said cams, and means

whereby said cam bar operates said reciprocatory bar.

Signed at Philadelphia, in the county of 10 Philadelphia, and State of Pennsylvania, this 7th day of November, 1921.

JOHN TAMBERLIN.
